UNITED STATES PATENT OFFICE.

SILAS M. FORD, OF ST. PAUL, MINNESOTA.

PLASTER-BOARD.

1,301,828.

Specification of Letters Patent. Patented Apr. 29, 1919.

Application filed May 25, 1916. Serial No. 99,820.

To all whom it may concern:

Be it known that I, SILAS M. FORD, a citizen of the United States, residing at St. Paul, in the county of Ramsey and State of Minnesota, have invented certain new and useful Improvements in Plaster-Board, of which the following is a specification.

My invention relates to improvements in plaster board of waterproofed paper or other fibrous sheeting corrugated to form lath projections and intermediate valleys or depressions, and designed to be secured to the studding or beams of buildings to form a foundation for plaster.

The object of the invention is to provide a lath-board of that character wherein the valleys or depressions upon the face of the board to which the plaster covering is to be applied are filled with plaster, mortar, or other cementitious material to form a key base to which the applied plaster will readily adhere, as well as to assist in holding the corrugations to form and to prevent them from being crushed in handling so as to impair their capacity as air containing or plaster receiving spaces. The valleys can be filled with this cementitious filling at the factory or other convenient place before the board has been put in place upon the side walls or ceilings of the building at a cost usually much less than if the plaster were filled into the board after the same was put in place.

A further object of the invention is to provide improved means for securely keying or locking the cementitious filling to the corrugated board and for binding the corrugations together. As the cementitious material will be filled into the valleys when in plastic condition it will adhere to the corrugated board itself, but I prefer to employ more positive means for holding the cementitious filling to the board and also for binding the corrugations together, thereby enabling me to form corrugations of rectangular shape, if so desired, where the entire outer surface of the filling is exposed and where none of it is held under overlying sides of the cor-

rugations as would be the case where they are of dove-tailed or keyed lath shape.

To these ends I have threaded cords or equivalent fibrous instrumentalities through the board so that the same shall pass into and preferably transversely through the valleys which are to be filled with cementitious material, so that when the cementitious material has set it will firmly grip and adhere to these fibrous instrumentalities.

More particularly the invention consists in the construction, combination and arrangement of parts hereinafter described and claimed.

In the accompanying drawings showing embodiments of the invention,

Figure 1 is a perspective view of a fragment of the corrugated board with its cementitious filling and fibrous anchoring devices.

Fig. 2 is a plan view of a fragment of the board looking down upon the plastering face thereof before the cementitious material has been filled in.

Fig. 3 is a bottom view of a fragment of the board showing the cords passing through the sheet on the under side of the valleys, and

Fig. 4 is a plan view of a fragment of the board showing a modified arrangement of anchoring cords as they appear before the cementitious material has been filled in.

The lath board which is the subject of this invention is made of fibrous sheeting, preferably waterproofed paper, pressed or molded to form corrugations, or alternate lath projections and intermediate depressions or valleys, the projections on one side forming the depressions on the other side, and vice versa. These corrugations may be of any desired shape, but are preferably rectangular in cross-section so as to expose upon the plastering face of the board as much of the cementitious filling as is possible without making the sheet liable to separate from the fillings when under pressure as would be the case if the sides of the projections were flared outwardly.

In the drawings 2 represents the lath projections upon the outer or plastering face of the board, and 3 the projections on the under face of the board. The corrugations 5 are shown as rectangular in cross section having upright sides 4 which are common to the lath projections 2 upon the outer face of the board and the opposite adjacent projections 3 on the under side of the board. Between the lath projections 2 are depressions 5 where the oppositely directed projections 3 are stamped out, while between the lath projections 3 are similar but oppositely facing depressions 6 formed by 15 stamping out the projections 2.

Through the bottoms or sides of the projections 3 upon the underside of the board are threaded or passed cords or other fibrous instrumentalities which enter the valleys or 20 depressions 5 above these projections and serve as keys or locking means to hold the cementitious material to be filled into these valleys as hereinafter explained.

In Figs. 2 and 3 the fibrous locking means 25 is shown as a continuous cord stitched through the board portion 3 so as to form a sort of lock stitch 7 but the method of threading is not essential so long as it affords within the depressions 5 a considerable number 30 of exposed holding ends or parts to which cementitious material can adhere. For instance, in Fig. 4 the cord is shown threaded through the board portions 3 so as to form merely a series of straight loops 8. Obviously the method of threading the cord through the sheet can be varied in any desired way, and instead of having one long cord threaded in and out through the board, a number of short pieces of cord can be used, 40 even so short as to allow of being passed only once through the sheet.

After the cords have been thus incorporated in the board, plaster, mortar or other cementitious material 9 is filled into the valleys 5 while it is in a plastic state, and allowed to set and harden. As it sets the cementitious filling will firmly grip and adhere to the board at the bottoms and sides of the valleys, and particularly to the cord portions at 50 the bottoms thereof so that it will form an integral part of the board, which then can be shipped in large sheets and cut to the desired size at the place of use.

While the cords at the bottoms of the valleys 55 will hold the cementitious material firmly to the board at the bottoms of the valleys, the side portions 4 of the corrugations will be held to the cementitious filling only by the adhesion between the board and the fillings. In order absolutely to prevent the sides 4 of the corrugations from being pulled away from the cementitious fillings under tensile or other strains upon the board, I prefer to pass the cords 10 transversely

through the corrugations below the plastering faces of the projections 2, as shown in Fig. 1, before the cementitious material has been filled in. These cords will pierce the side walls 4 of the corrugations and pass through and across the valleys 5 to be filled 65 with the cementitious material so that when this material has been filled in, it will adhere to the cords 10 as well as to the side walls 4 and prevent the corrugations from being pulled apart under any ordinary strain to 70 which they may be subjected. With the use of the transverse cords 10 it is possible to dispense entirely with the anchoring cords in the bottoms of the valleys, but I prefer to 75 use both forms of lock.

By the term cord as here used is meant any fibrous instrumentality which will act in substantially the same way as a cord.

I claim:

1. As an article of manufacture, a plasterboard comprising a sheet of fibrous material corrugated to form interspaced lath projections and intermediate valleys, anchoring instrumentalities passing through the board and into the valleys on the plastering face of 85 the board, and fillings of cementitious material disposed lengthwise of said face-valleys and filling the same, and adherent to said anchoring instrumentalities.

2. As an article of manufacture, a plasterboard comprising a sheet of fibrous material corrugated to form interspaced lath projections and intermediate valleys, cords passing through the board and into the valleys on the plastering face of the board, and fillings of 90 cementitious material disposed lengthwise of said face-valleys and filling the same, and adherent to said cords.

3. As an article of manufacture, a plasterboard comprising a sheet of fibrous material 105 corrugated to form interspaced lath projections and intermediate valleys, cords threaded through the bottoms of the face valleys and projecting into the same, and fillings of cementitious material disposed lengthwise of 110 said face valleys and filling the same and adherent to said cords.

4. As an article of manufacture, a plasterboard comprising a sheet of fibrous material corrugated to form interspaced lath projections and intermediate valleys, cords passing transversely through the corrugations and traversing the valleys on the plastering face of the board, and fillings of cementitious material arranged lengthwise of said face-valleys and filling the same, and adherent to 115 said cords.

5. As an article of manufacture, a plasterboard comprising a sheet of flexible material corrugated to form interspaced lath projections and intermediate valleys, anchoring cords passing through the bottoms of the face valleys and extending up into the same, bind-

ing cords passing transversely through the sides of the corrugations and traversing said valleys, and fillings of cementitious material disposed lengthwise of said face valleys and 5 filling the same and adherent to said cords.

6. As an article of manufacture, a plaster-board comprising a sheet of fibrous material corrugated to form interspaced lath projections and intermediate valleys, cords thread-10 ed through the bottoms of the face valleys

and extending up into and along the same, and fillings of cementitious material disposed lengthwise of said valleys and filling the same and adherent to said cords.

In testimony whereof I affix my signature 15 in presence of two witnesses.

SILAS M. FORD.
